X-RAY APPARATUS

Herbert A. Newman, Delavan, Wis., assignor to
The George W. Borg Corporation, Delavan,
Wis., a corporation of Delaware

Application May 11, 1949, Serial No. 92,609

2 Claims. (Cl. 250—59)

1

The present invention relates in general to X-ray Apparatus, but more in particular to X-ray tables which are equipped for spot film radiography. The object of the invention is a new and improved arrangement for enabling the operator, when about to make a spot film radiograph, to quickly and accurately select the proper kilo-voltage.

One factor which determines the kilo-voltage to be used is the distance between the film and the focal spot of the X-ray tube. In spot film radiography the tube is supported beneath the table and while the distance from the focal spot of the tube to the surface of the table top is fixed, or is known, the case is different as regards the distance between the surface of the table and the spot film device. The spot film device, containing the film, extends horizontally above the top of the table and above the body of a patient lying thereon, and is adjustable up and down in accordance with the thickness of the patient's body or of the part to be examined. The spot film device must be adjusted close against the body and hence the distance from the film to the surface of the table and to the focal spot of the tube is variable, over a considerable range.

In view of the foregoing it is impossible to accurately set the kilo-voltage selector prior to examination of the patient. This must be done with the patient on the table. After he has been adjusted properly, usually by fluoroscopic examination, and the operator is ready to make the radiograph, it is desirable to be able to quickly determine the kilo-voltage to use so that the exposure can be made before the position is disturbed.

The problem thus presented is solved in accordance with the invention by provision of an arrangement which includes a scale on the spot film tower and an index movable with the spot film device for cooperation with the scale. The scale is calibrated in accordance with kilo-volts to be added to or subtracted from a predetermined standard kilo-voltage which is known to be suitable for the average body thickness.

The invention will be described more in detail in the specification which follows, reference being had to the accompanying drawing, in which—

Fig. 1 is a side elevation of an X-ray table embodying the invention;

Fig. 2 is an enlarged view of the scales and index member; and

Fig. 3 shows the compression cone which may be used with the spot film device.

Referring to the drawing, the reference character 10 indicates an X-ray table of known construction, having the base 11 upon which it is mounted in known manner. The table comprises side members 12 and 13 which are secured together in spaced relation, and a top 14 which is supported a short distance above the side members.

2

The reference character 15 indicates the fluoroscopic carriage and shutter assembly, which is supported on the side members 12 and 13 by means of ball bearings and steel tracks (not shown) and is movable lengthwise of the table. Depending from the carriage is a lead lined cone 16 at the lower end of which the X-ray tube 17 is supported in any suitable manner.

The carriage 15 includes a part which extends to the rear of the table beneath the top 14, where it is attached to and supports the vertical spot film device tower 18. The spot film device is indicated at 19 and may be similar to the device shown in U. S. Patent No. 2,184,962, granted December 26, 1939.

The spot film device is pivotally supported on the elevator 28 and may be raised to a vertical position where it is out of the way. When in use it extends forward horizontally above the top of the table as shown. The elevator 28 is movable up and down on the tower 18 in order to adjust the distance between the table top and the spot film device, for the purpose previously mentioned. Means is also provided for locking the elevator with the spot film device in any desired position. These arrangements are known and since the details thereof are not involved in the invention it has not been considered necessary to show them in the drawing. The reference characters 20 and 21 indicate metallic strips which are fastened to the front of the tower 18 and which carry the scales suitably stamped, embossed or printed thereon as shown in Fig. 2. The strip 20 at the right carries the kilo-voltage scale, marked "P. K. V." at the top, while strip 21 carries a centimeter scale marked "CM."

The index member 22 is preferably made of sheet metal, like the scale strips 20 and 21, and has a forwardly extending part 30 by means of which it is attached to the top of elevator 28. The index member accordingly moves up and down with the spot film device as the latter is adjusted to the patient's body. It has two arrows labeled "Cone Compr." and "No Compr." respectively, which cooperate with the kilovoltage and centimeter scales on strips 20 and 21. While the lower arrow is obscured by the spot film device 19 in Fig. 1, it is visible to the operator looking down on the apparatus from above the patient, since there is some space between the rear of the spot film device and the front of the elevator.

Referring to the centimeter scale it will be noted that there is a scale division marked "AVG." and that the scale is calibrated from 1 to 15 toward the bottom and also from 1 to 15 toward the top. These calibrations are in centimeters and make it possible to read directly if the body of a patient on the table is of average thickness or not, and if not, how much it departs in either direction from the average thickness. When the arrow marked "No Compr." is opposite the scale division marked "AVG." the film is 21

centimeters above the table top. This distance has been determined by measurements of a large number of individuals which show that the average body thickness in the stomach region, where spot film radiographs are taken, is 21 centimeters. If the arrow points to "AVG.", therefore, after the spot film device is adjusted, the operator knows that the patient's body is of average thickness, and he knows also that the thickness is 21 centimeters. If the arrow points to some scale division above or below average, on the other hand, the operator can read directly how much the body thickness exceeds or is less than the average. In Fig. 2, for example, the arrow indicates that the body thickness is 5 centimeters less than average.

The information as to body thickness thus supplied is of value in certain techniques, as will be readily understood. If in any case the operator desires or needs to know the actual distance between the film and table top he merely has to add or subtract the number of centimeters shown by the arrow or indicator to or from the value of 21 centimeters. Thus in Fig. 2 the distance indicated is 21 centimeters less 5 centimeters, or 16 centimeters.

Referring now to the kilo-voltage scale "P. K. V." on the right, the center division of the scale is marked "AVG.", as in the case of the centimeter scale. Also like that scale, the kilo-voltage scale is calibrated in both an upward and downward direction from "AVG.". The calibrations are in kilo-volts and by cooperation with the No Compr. arrow indicate to the operator the number of kilo-volts to be added to or subtracted from a standard kilo-voltage in order to obtain the correct kilo-voltage setting for any given patient.

Further explaining the foregoing, the operator has a standard technique adapted for spot film radiography which has been worked out experimentally and which depends on the use of a certain standard kilo-voltage for making a radiograph of a person with average body thickness. This standard kilo-voltage may be, for example, 60 kilo-volts. If the body is thicker than average the kilo-voltage has to be increased while if it is thinner than average the kilo-voltage should be correspondingly reduced. After the spot film device has been adjusted properly the No Compr. arrow shows directly the amount of addition or subtraction required.

In Fig. 2, for example, the arrow shows that 10 kilo-volts should be subtracted from the standard of 60 kilo-volts and the operator knows at once, therefore, that the kilo-voltage selector should be set to 50 kilo-volts. For another example, it may be assumed that when the spot film device is properly adjusted the index member 22 is in a more elevated position by reason of the greater thickness of the patient's body, so that the arrow points to the numeral 6 in the upper half of the scale. This indicates to the operator that the standard kilo-voltage should be increased by 6 kilo-volts and that the correct setting of the kilo-voltage selector is 66 kilo-volts.

The compression cone 25, Fig. 3, is secured to a plate 24 which may be slid between the guides 26 and 27 at the bottom of the frame of the spot film device 19, Fig. 1. The use of the compression cone is well known so it will not be necessary to explain it herein. It will suffice to point out that when attached to the spot film device the compression cone produces the same effect as an

increased body thickness, and makes it necessary to use a higher kilo-voltage. This is taken care of by the provision of another arrow or indicator marked "Cone Compr." which is used by the operator to read the kilo-voltage correction at times when the cone is in use. This arrow gives readings calling for kilo-voltages which are 10 kilo-volts higher than those called for by corresponding readings with the other arrow. This value depends on the depth of the cone and consequently it is desirable to use the one furnished with the machine or another one having the same dimensions.

The invention having been described that which is believed to be new and for which the protection of Letters Patent is desired will be pointed out in the appended claims.

I claim:

1. In combination, an X-ray table comprising side members and a top supported thereon, a carriage supported on said side members beneath said top and movable lengthwise of the table, an X-ray tube supported on said carriage beneath said top and at a predetermined distance therefrom, a tower supported on said carriage at the rear of said table and extending vertically upward above the top thereof, a spot film device supported on said tower above the table top, means for adjusting said spot film device up or down to engage the body of a patient lying on said table, an indicator connected to said spot film device to move therewith, a member supported on said tower and carrying a fixed scale arranged to co-operate with said indicator throughout the range of movement thereof, a generally central division mark on said scale opposite which said indicator is disposed when said spot film device is adjusted to a patient of average body thickness, the position of said division mark being so related to the sum of average body thickness and the distance between the X-ray tube and table top that when the indicator is opposite said division mark it indicates a predetermined average kilo-voltage which is standard for that condition, a plurality of other division marks on said scale extending above and below said central division mark, and numerals associated with said other division marks, said numerals having selected values such that when the indicator is opposite any one of said other division marks the associated numeral will show the number of kilo-volts to be added to or subtracted from said standard kilo-voltage.

2. The combination as claimed in claim 1, wherein the spot film device has a detachable compression cone for insertion between the spot film device and the patient's body, and a second indicator is provided for cooperation with the division marks on said scale when said cone is used, said second indicator being spaced away from the first indicator by a distance depending on the depth of the cone.
